GLEN WINDLE, OF CHARDON, KANSAS.

CLOTHES-HOOK.

1,260,846.

Specification of Letters Patent. Patented Mar. 26, 1918.

Application filed May 29, 1917. Serial No. 171,773.

To all whom it may concern:

Be it known that I, GLEN WINDLE, a citizen of the United States, residing at Chardon, in the county of Rawlins and 5 State of Kansas, have invented new and useful Improvements in Clothes-Hooks, of which the following is a specification.

This invention relates to supports, and more especially to clasping hooks; and the 10 object of the same is to produce a support of this character by means of which articles of clothing and the like may be sustained in such manner that they cannot be accidentally dislodged from the hook and thrown 15 to the floor, as is so often the case with clothes hooks which are put up in crowded places.

This object is carried out by constructing the hook with a guard which normally lies 20 across its throat and is held in active position by the weight of the clothing or other garment hung on the hook. Details of two types of this invention are set forth in the following specification and shown in the accompanying drawings wherein:

Figure 1 is a perspective view of one form, of my hook with a garment hung thereon.

Fig. 2 is a side elevation of this type of 30 my invention, showing its parts in full lines with the hook dropped and the guard raised to open condition, and in dotted lines as moved past what I call a "dead-center" toward its closed position.

Fig. 3 is a side elevation of another type 35 of this hook, showing its parts as closed, and Fig. 4 is a vertical section on the line 4—4 of Fig. 3.

Either type of my hook includes a base 40 mounted on an upright support which in the present case is the wall W. This base may be secured to the wall in any appropriate manner, and it may be in one piece or two pieces so long as it provides two bearings 1 and 2 which in Fig. 4 are shown as parts of a plate 3 standing upright and attached to the wall W by fastening means such as screws 4. However, these bearings 45 might be two separate elements screwed into or attached to the wall W in any appropriate manner. Collectively they make up the base member.

Mounted in the upper bearing is a guard 5 which is shown in the drawings is made 55 of a single piece of wire bent into appropriate shape, and preferably having sub-

stantially parallel side arms, in each of which is formed an eye 6. These arms are connected at their outer ends, and in Fig. 4 they are shown as upturned into a supplemental hook 7 which will be described below.

Mounted in the lower bearing 2 is a loop 10 which is substantially rectangular, and this also may be made of a single piece of 65 wire bent into approximately square form as shown.

The hook is also shown as made of a single piece of wire bent into parallel arms integrally connected at their outer ends, and the 70 shank 11 of this hook is turned upward at right angles at its inner end, the arms of the shank having eyes 16 at the angles in which the outer cross bar of the loop is pivoted. Above these eyes the arms of the 75 shank rise in substantial parallelism with the base plate on the face of the wall, and at their upper ends they are turned inward toward each other and pivotally mounted in the eyes 6 as shown. The outer or forward 80 end of the hook-shank is turned upward into a bill 14, and the bill is so disposed that the guard comes down over its tip when there is a load on the hook as indicated at L in Fig. 1. Over the working parts of the hook and 85 the guard may be coiled fine wire as indicated at 20, in order to prevent articles of clothing from slipping off these members when placed thereon. The wire may be of any suitable gage, and in fact I do not wish 90 to be limited to the use of wire, as the elements of this device may be of other material, perhaps castings. Where the parts are pivoted in the eyes, or where the members 95 are journaled in the bearings they may be surrounded by sleeves to reduce friction, but this detail has not been illustrated as it forms no part of the present invention.

With the parts of my invention standing in full lines as seen in Fig. 2, the pivot at 100 the outer end of the loop in the eyes 16 has passed a dead center point, that is, it has passed a straight line between the eyes 6 and the lower bearing 2, and this intermediate pivot now rests against the base plate. 105 Therefore the parts will remain in this position, even though a garment be hung on the bill of the hook. When now it is desired to use the device, the garment is placed on said bill and then drawn forward a little. This 110 moves the pivots in the eyes 16 to the dotted position in the same view, where it has

passed the "dead-center" and now by moving the outer end of the guard downward until it contacts with the upwardly moving tip of the bill of the hook, the parts assume 5 the position shown in Fig. 1 and the garment is reliably held on the hook by means of the guard and can not be removed therefrom by accident. Hence it is not likely to be brushed off the hook by persons who may 10 pass the same in aisles or other places where garments are stored. To remove it, it is necessary to raise the guard, and this causes the automatic descent of the hook which is assisted by the weight of the garment itself. 15 Continued rise of the guard finally brings the parts to the dotted position in Fig. 2, and eventually past the dead center and to the full-lined position, when the garment may be removed and the fastening hook will 20 stand in this position until used again.

The other type of my invention illustrated in Figs. 3 and 4 is almost identically the same excepting that the forward end of the guard is here turned into a supplemental 25 hook or bill which rises from the body of the guard in a plane beyond the bill of the main hook. The result is that an article of clothing such as a coat may be hung on the main hook, and subsequently another article of 30 clothing such as a hat may be hung on the supplemental hook. My invention will commend itself to those who are fitting out rooms where large numbers of garments have on occasions to be stored, such, for instance, as hallways, dressing rooms, and 35 racks in hotels, dance halls, and other places of similar nature. I have abstained from giving details as to proportions and materials of parts, as they are not essential.

Copies of this patent may be obtained for five cents each, by addressing the "Commissioner of Patents, Washington, D. C."

What is claimed as new is:—

1. In a clasping hook, the combination with a base plate secured to an upright support and having two bearings, and a guard mounted at its inner end in the upper bearing and having eyes adjacent said end; of 45 a hook having a right-angular shank whose inner end is pivotally mounted in said eyes, whose angle carries a pair of eyes, and whose bill is upturned, and a loop mounted in the lower bearing of the base plate and in the 50 eyes at the angle of said hook, the eyes in the angle of said shank being adapted to pass a straight line between the lower bearing and the eyes in the guard, the whole for use substantially as described. 55

2. In a clasping hook, the combination with an upright base plate having upper and lower bearings, a guard mounted in the upper bearing and projecting forward therefrom, the guard comprising substantially 60 parallel side arms having eyes adjacent said bearing, and a rectangular loop mounted in the lower bearing on said base plate; of a hook having a right-angular shank composed of substantially parallel arms bent at 65 their angles into eyes in which the outer end of said loop is mounted, their extremities being turned inward and mounted in the eyes of the guard, the outer end of said arms being integrally united in a hook-bill over 70 which the guard is adapted to lie, the eyes in the angles of said shank being adapted to pass a straight line between the lower bearing and the eyes in the guard, for the purpose set forth. 75

In testimony whereof I affix my signature.

GLEN WINDLE.
